UNITED STATES PATENT OFFICE

JAMES G. BLUNT AND HARRY S. BURNHAM, OF SCHENECTADY, NEW YORK

LOCOMOTIVE

Application filed May 26, 1930. Serial No. 455,499.

This invention relates generally to articulated locomotives, and has for an object the provision of a locomotive structure embodying at least two longitudinally spaced engines, each comprising two duplicate castings, each casting having a half saddle, a working cylinder, and a distribution valve chest, the half saddles being so formed at their tops that when combined they will provide a horizontal shelf adapted to support either a boiler bearing or a platform, all of the half saddle and cylinder castings being of the same form and interchangeable one with the other.

Another object of the invention is to provide a locomotive structure embodying at least two longitudinally spaced engines, each engine comprising in an integral casting a plurality of working cylinders, a plurality of distribution valve chests, and a cylinder saddle, the cylinder saddle being formed at its top with a horizontal shelf adapted to support either a boiler bearing or a platform, the two castings being duplicates and interchangeable one with the other.

Other objects of the invention will hereinafter readily appear.

The improvement claimed is hereinafter fully set forth.

In the accompanying drawings: Figure 1 is a fragmentary side elevation of the forward portion of a locomotive embodying the invention; Fig. 2, a view showing the assembly of two of the half saddle and cylinder castings, one of the castings being shown in transverse vertical section on the line II—II of Fig. 3, and the other casting being shown in end elevation; Fig. 3, a fragmentary top plan view of one of the castings shown in Fig. 2; Fig. 4, a transverse section taken on the line IV—IV of Fig. 2; Fig. 5, a view of one of the half saddle and cylinder castings shown in Fig. 2, one half being an elevation of the outer side thereof, and the other half being an elevation of the inner side thereof; Fig. 6, a fragmentary end view of a modified form of construction wherein two cylinders, two valve chests, and a cylinder saddle are combined in an integral or one piece

casting; and, Fig. 7, is a transverse section taken on the line VII—VII of Fig. 6.

In the practice of the invention, referring to the specific embodiment thereof selected for exemplification herein, the locomotive comprises a boiler 10, a front main frame section 11, articulated to a rear main frame section 12. Supported on the front end of the rear main frame section 12, is a steam engine 13, and supported on the front end of the front main frame 11, is a steam engine 14. Each steam engine embodies two duplicate castings, each casting comprising a working cylinder 15; a distribution valve chest 16; a half saddle 17; a flanged steam delivery passage 18, leading to the valve chest; an exhaust passage 19, leading from the valve chest through the saddle from the front end thereof to the rear end thereof; a plug 20, closing one end of the exhaust passage; and a flat horizontal shelf portion 21 at the top of the saddle. When two of the castings are combined to form an engine, the shelf portions 21 thereof constitute a flat shelf 22 adapted to support either a boiler bearing or a platform. Mounted on the shelf 22 of the engine 13 is a boiler bearing 23, and mounted on the shelf 22 of the engine 14 is a flat plate or platform 24. The inner end of each half saddle is formed with a guide recess 25 for a centrally disposed reverse gear reach rod 26.

When it is desired to transfer one of the cylinder and half saddle castings from one side of the locomotive to the other, the closure plug 20 at one end of the exhaust port may be transferred to the opposite end thereof.

The cylinder and half saddle castings of both of the engines being counterparts, it will be obvious that all of the castings can be interchanged one for the other, thus enabling the four castings to be formed from the same pattern, and the number of stock castings required for replacements to be greatly reduced.

In the modification shown in Figs. 6 and 7 of the drawings, there are combined in a single integral casting, two working cylinders 27; two distribution valve chests 28; a full cylinder saddle 29; a flat horizontal shelf 30 at the top of the saddle, adapted to sup-

port either a boiler bearing or a platform; a reach rod guideway 31, disposed centrally of the saddle; and an exhaust passage 32 having branches leading from each end of the valve chests to a central portion which opens at one end of the casting. It will be obvious that the modified form of construction enables the combined casting to be used for either the front or the rear engine. Fig. 6 10 illustrates the casting of the front engine, on the shelf 30 of which is supported a platform 33.

While but two forms of construction have been described and shown, it is obvious that 15 many variations in procedure, form, arrangement, and construction of parts, may be resorted to, and the invention, therefore, is not limited to the particular embodiment disclosed, but includes such changes and modifications as come within the spirit and scope 20 of the invention as set forth in the appended claims.

The invention claimed and desired to be secured by Letters Patent is:

25 1. In a steam locomotive, the combination of two longitudinally spaced engines each comprising two duplicate castings, each casting having a working cylinder and a half saddle, the half saddle being formed at its top with a portion constituting one half of a shelf adapted to support either a boiler bearing or a platform, the four castings constituting the two engines being counterparts and interchangeable one with the other.

35 2. In a steam locomotive, the combination of two longitudinally spaced engines each comprising two duplicate castings, each casting having a working cylinder, a distribution valve chest, and a half saddle, the half saddle being formed at its top with a portion constituting one half of a shelf adapted to support either a boiler bearing or a platform, the four castings constituting the two engines being counterparts and interchangeable one 40 with the other.

50 3. In a steam locomotive, the combination of two longitudinally spaced engines each comprising two duplicate castings, each casting having a working cylinder, a distribution valve chest, a half saddle, and an exhaust passage leading through the front and rear of the casting, the half saddle being formed at its top with a portion constituting one half of a shelf adapted to support either a boiler bearing or a platform, the four castings constituting the two engines being counterparts and interchangeable one with the other.

55 4. In a steam locomotive of the articulated type, the combination of a boiler; two main frame sections; an articulated connection joining the two main frame sections; two steam engines, one mounted on each of the main frame sections, each steam engine comprising two duplicate castings, each casting 60 having a working cylinder and a half saddle,

the half saddle being formed at its top with a portion constituting one half of a shelf adapted to support either a boiler bearing or a platform, the four castings constituting the two engines being counterparts and interchangeable one with the other; a boiler bearing mounted on the shelf of one of the engines; and a platform mounted on the shelf of the other engine. 70

5. In a steam locomotive of the articulated type, the combination of a boiler; two main frame sections; an articulated connection joining the two main frame sections; two steam engines, one mounted on each of the main frame sections, each steam engine comprising two duplicate castings, each casting having a working cylinder, a distribution valve chest, and a half saddle, the half saddle being formed at its top with a portion constituting one half of a shelf adapted to support either a boiler bearing or a platform, the four castings constituting the two engines being counterparts and interchangeable one with the other; a boiler bearing mounted on the shelf of one of the engines; and a platform 80 mounted on the shelf of the other engine. 85

6. In a steam locomotive of the articulated type, the combination of a boiler; two main frame sections; an articulated connection joining the two main frame sections; two steam engines, one mounted on each of the main frame sections, each steam engine comprising two duplicate castings, each casting having a working cylinder, a distribution valve chest; a half saddle, and an exhaust passage leading through the front and the rear of the casting, the half saddle being formed at its top with a portion constituting one half of a shelf adapted to support either a boiler bearing or a platform, the four castings constituting the two engines being counterparts and interchangeable one with the other; a boiler bearing mounted on the shelf of one of the engines; and a platform mounted on the shelf of the other engine. 100

7. In a steam locomotive, the combination of two longitudinally spaced engines, each engine comprising an integral casting, each casting embodying a full cylinder saddle, two working cylinders one on each side of the saddle, and a shelf adapted to support either a boiler bearing or a platform, the two castings being counterparts and interchangeable. 115

8. In a steam locomotive, the combination of two longitudinally spaced engines, each engine comprising an integral casting, each casting embodying a full cylinder saddle, two working cylinders one on each side of the saddle, two distribution valve chests, and a shelf adapted to support either a boiler bearing or a platform, the two castings being counterparts and interchangeable. 120

9. In a steam locomotive, the combination of two longitudinally spaced engines, each engine comprising an integral casting, each 125

5 casting embodying a full cylinder saddle, two working cylinders one on each side of the saddle, two distribution valve chests, an exhaust passage leading from each of the valve chests through an end wall of the casting, and a shelf adapted to support either a boiler bearing or a platform, the two castings being counterparts and interchangeable.

10 10. In a steam locomotive, the combination of two longitudinally spaced engines, each engine comprising a structure embodying a right hand and a left hand working cylinder, a cylinder saddle, and a shelf at the top of the saddle adapted to support either a boiler bearing or a platform, the said structures of the two engines being counterparts, and adapted to be interchanged one for the other.

15 11. In a steam locomotive, the combination of two longitudinally spaced engines, each engine comprising a structure embodying a cylinder saddle, a working cylinder integrally united to the saddle, and a shelf at the top of the saddle adapted to support either a boiler bearing or a platform, the said structures of the two engines being counterparts and adapted to be interchanged one for the other.

20 12. In a steam locomotive, the combination of two longitudinally spaced engines each comprising two duplicate structures, each structure comprising a working cylinder and a half saddle, the half saddle being formed at its top with a portion constituting one half of a shelf, and a boiler bearing supported on 25 one of the shelves, the said four structures comprised in the two engines being counterparts and interchangeable one with the other.

25 13. In a steam locomotive, the combination of two longitudinally spaced engine structures, each comprising a full cylinder saddle, two working cylinders one on each side of the saddle, and a shelf at the top of the saddle, the two structures being counterparts and interchangeable one with the other, and a boiler 30 bearing supported on one of the shelves.
